BINDER TENSIONING TOOL

Alfred Marchev, La Grange, Ill., assignor to
Signode Steel Strapping Company, Chicago,
Ill., a corporation of Delaware

Application February 10, 1939, Serial No. 255,612

12 Claims. (Cl. 254—66)

My invention relates to binder tensioning tools. More particularly it relates to a tool for tensioning bundle-binders of the flat strap variety.

5 An object of the invention is to provide an improved tool which, although not limited to such use, is particularly adapted to tension binder strap about small incompressible packages.

Another object is to provide a tool having a 10 strap-edge type of gripper which is an improvement upon the one set forth in the patent application of Albert F. Pagel, Serial No. 245,628, filed December 14, 1938.

Another object is to provide a tool with improved arrangements for releasing the strap grippers.

20 A further object is to provide a tool with an improved arrangement for severing the completed bundle encircling loop from the source of strap supply.

Other objects and advantages will hereinafter appear.

Fig. 1 is a side elevation of the tool, showing it resting in a typical position on a package being 25 bound;

Fig. 2 is a top plan with the actuating handle in section;

Fig. 3 is a bottom plan of the strap edge gripper;

30 Fig. 4 is a section on the line 4—4 of Fig. 2;

Fig. 5 is a section on the line 5—5 of Fig. 2;

Fig. 6 is a rear elevation of the strap edge gripper;

Fig. 7 is a section on the line 7—7 of Fig. 2;

35 Fig. 8 is a section on the line 8—8 of Fig. 2;

Fig. 9 is a side elevation of the portion of the tool shown in section in Fig. 8;

Fig. 10 is a section on the line 10—10 of Fig. 1;

Fig. 11 is a section on the line 11—11 of Fig. 1;

40 Fig. 12 is a bottom plan similar to Fig. 3, showing the strap edge gripper arranged to accommodate a narrower strap, and

Fig. 13 is a diagrammatic view illustrative of the operation of binding a package.

45 In general the tool comprises a foot A, equipped with a strap-edge gripper and a rack and in use normally resting on and supported by the package P being bound, a relatively movable carriage B carried by the rack and provided with another 50 strap gripper and mechanism for propelling it along the rack, a tensioning handle C for actuating the propelling mechanism and controlling the strap gripper of the carriage B and a gripper control handle D for controlling the strap-edge 55 gripper of the foot A.

The foot A has a relatively flat base 15 which is provided with a strap channel 16 in its under side or lower face. In Fig. 3 the location of one of the strap ends in channel 16 during the tensioning operation is indicated by the dash lines. 5 A fixed gripper member 17 is located at one side of channel 16 and a movable gripper member 18 is located at the other side of the channel, opposite gripper 17. These two gripper members are arranged to grip a strap end portion edgewise 10 between them so as to anchor it.

Fixed gripper 17 preferably comprises a flat steel plate having hardened teeth or serrations 19 in its front face and being rigidly secured in a recess 20 of base 15 by set screws 21. Thus, the insert fixed gripper member 17 can be readily removed and replaced should occasion require and, by substituting plates of different lengths, so as to vary the distance the gripping edge projects into channel 16 toward gripper member 18, 20 the tool may be modified to act upon straps of different widths with a definite invariable limit of travel for the movable gripper member. Base 15 provides a seat for a rack bar 26, the bar being rigidly anchored to the base by a cap 27 and cap screws 28 that thread into the base. As previously mentioned, rack bar 26 carries the movable gripper carriage B.

Gripper carriage B includes a frame having 30 parallel upstanding bearing flanges 30, 31 and a laterally projecting gripper foot 32. It also has a laterally projecting curved flange 33 in the inner curve of which is rotatably seated a pivoted gripper member 34 which, preferably is toothed or serrated on its lower end and is pivoted by a shaft 35 that has bearings in flanges 30 and 31, as shown most clearly in Fig. 10. The relation between gripper foot 32 and pivotal gripper member 34 is such that, by movements of gripper member 34, they may be separated to provide a laterally open gap for the insertion of a strap end portion and caused to approach in order to anchor the strap end portion by a flatwise or surface clamping action.

45 Shaft 35 is retained in place by a pair of nuts 36 and 37 which thread upon its opposite ends and bear against flanges 30 and 31, respectively. Rotation of shaft 35 causes rotation of pivoted gripper 34 and the shaft is in turn rotated by a 50 gripper actuating finger 38, as will be hereinafter explained. The rotation together of gripper 34, shaft 35 and finger 38 may be effected in various ways. I prefer to provide the shaft with squared portions 39 and 40 which fit correspondingly 55

squared holes through gripper 34 and finger 38, as shown most clearly in Fig. 10.

Tensioning handle C, the lower end of which is preferably bifurcated into two spaced parallel sections 45 and 46, is pivoted to and between flanges 30—31 of carriage B on a pivot screw 47. A pinion 48 is loosely journaled on screw 47 between the bifurcated sections 45 and 46 of handle C and in a position to mesh with the teeth of rack bar 26. An actuating pawl 49 is likewise located between the bifurcation-sections 45 and 46 of handle C, being fixed to a shaft 50 journaled in sections 45 and 46 and positioned to mesh with the teeth of pinion 48. A spring-pressed plunger 51 carried by handle C bears upon the rear end of pawl 49 yieldingly to bias the forward end thereof toward pinion 48 so that rotation of handle C about its axis 47 in a clockwise direction, as shown in Figs. 1 and 7, causes clockwise rotation of the pinion 48—and consequently movement of carriage B toward the right or away from the foot A; whereas, upon rotation of handle C in the reverse or counterclockwise direction, the pawl 49 can ride idly over the teeth of pinion 48 in the reverse direction. A pair of spring biased holding pawls 51 and 52 are pivotally mounted on shaft 35, being provided with teeth 53 and 54, respectively, to engage the teeth of pinion 48 to prevent reverse rotation thereof. By using two holding pawls, one arranged half a tooth ahead of the other, as shown most clearly in Fig. 7, the holding effect thereof is such that the pinion is retained on an advance of half the distance between teeth and thereby closer adjustments of strap tension are possible.

Pawls 51 and 52 have upwardly extending projections or tails 55 and 56, respectively, which are in position to be struck and operated by pawl 49 when the tensioning handle C is moved to its extreme counterclockwise position. Thus when handle C is oscillated through a limited arc, it rotates pinion 48 step-by-step and, in consequence, advances carriage B step-by-step along rack bar 26 (reverse movements being prevented by holding pawls 51 and 52), resulting in a gradual separation of foot A and carriage B and of the strap grippers carried thereby.

This separation of the grippers tensions the bundle encircling loop of strap binder, as will be presently explained. In order to provide for a quick slack take-up, I prefer to provide shaft 50 with a small lever or finger 57 whereby pawl 49 may be raised from engagement with pinion 48 to permit the carriage to be shoved along rack bar 26 in the gripper separation direction without the necessity of oscillating tensioning handle C. The tail of gripper control finger 38 is located where it will be engaged by handle C shortly after movement of the handle in a counterclockwise direction has caused the engagement of actuating pawl 49 with holding pawl 51 and 52 to free the pinion—and rack bar—from the effect of those pawls.

Further movement of the handle C after it has contacted finger 38—counter-clockwise as viewed in Figs. 1 and 2, clockwise as viewed in Figs. 3 and 9—will result in the rotation of shaft 35 and pivoted gripper member 34 to swing the gripper member away from foot 32 and thereby release the strap end portion anchored therebetween. Finger 38 is biased by a spring-pressed plunger 58 in a direction to cause the rotation of shaft 35 to bring gripper 34 into engagement with the upper surface of the strap to cause it

to be clamped against the underlying foot 32 to anchor it.

Gripper control handle D controls the action of movable strap-edge gripper member 18 through a rod 60. Handle D is pivoted by a screw 61 to a bracket 62 rigidly secured to rack bar 26 near its outer end. I prefer also to provide the end of rack bar 26 with a handle 63. Normally gripper control handle D is biased by a spring-pressed plunger 64 to its upper position, i. e., maximum separation from handle 63; but it may be rotated about its pivot 61 by the closing or squeezing action of the operator's hand, to bring its outer end closer to handle 63.

Rod 60 is slidably supported at its outer end in a guideway in bracket 62 and is connected to handle D by a pivot pin 65 that extends from the rod through a slot 66 in bracket 62 and into the lower or inner end of handle D. Rod 60 extends loosely through carriage B and a seat in base 15 and carries a pin 70 at its inner end. Pin 70 fits into a slot 71 of a bell crank lever 72. Lever 72 is pivoted to foot A by a headed stud 73, the stud being secured against displacement by a cotter pin 74 (see particularly Figs. 2 and 5).

Bell crank lever 72 is pivotally connected to strap-edge gripper member 18 by means of a pin 75. The relation between fixed pivot 73 and the movable gripper blade carrying pivot 75 should be such that as the bell crank lever 72 is rocked to carry the gripper blade 18 toward the strap, the strap edge is engaged slightly before the pivot 75 reaches a line through the center of pivot 73 and perpendicular to the strap edge. With this arrangement the movable edge gripper is self-tightening when it has engaged the strap edge, i. e., the grip increases as the tension on the strap increases.

When grip control handle D is squeezed toward handle 63, rod 60 is moved toward the left as viewed in Figs. 1, 2 and 3, with the result that bell crank lever 72 is rocked about its pivot 73 to withdraw or retract movable gripper member 18 further away from fixed gripper member 17 and thereby open the relatively stationary gripper for the reception of a strap end portion. When handle D is released its biasing spring-pressed plunger 64 automatically separates it from handle 63, with the result that rod 60 is moved to the right and bell crank lever 72 is rotated about its pivot 73 to cause the movable strap-edge gripper member 18 to approach the fixed edge-gripper member 17 and clamp by edgewise pressure a strap end portion interposed therebetween. A downwardly directed flange 76 of bell crank lever 72 is adapted to strike the edge of base 15 to limit the extent to which gripper 18 can approach gripper 17. By pivoting the movable edge gripper member 18, its active face will automatically adjust itself to parallelism with the strap edge and thereby insure a maximum of gripping contact with the edge.

In order to insure that a good edge grip is obtained upon the binder strap, that the strap end portion to be thus gripped is properly located between the relatively movable edge engaging jaws, that the edgewise pressure does not buckle the strap longitudinally and thereby weaken the clutch upon the strap, and that the tool can be readily separated from the tensioned bundle encircling strap loop, I have found it advantageous to bevel or taper the confronting strap edge en-

gaging faces of the two edge gripper members 17 and 18, as shown most clearly in Fig. 5.

I have found from actual experience that good results are obtained by sloping the active face 5 of gripper 17 about fifteen to twenty degrees from the vertical; and to curve the active face of gripper 18 on about a one-eighth inch radius. This arrangement provides, in effect, a tong-like pick-up for the strap, insures that the strap 10 remains between the jaws, insures, particularly if the strap begins to buckle outwardly, that the strap is pulled back against the bottom of the channel through base 15 and thereby reinforced to resist the buckling tendency and yet, when it 15 becomes desirable to remove the tool after the joint is made, the jaws do not sufficiently underlie the strap edges either to prevent ready disengagement from the strap or to interpose enough of the tool between the binder loop and 20 the bundle to render the tensioned loop objectionably loose after the tool has been removed.

The strap breaker or kinker, whereby the run of strap from the bundle encircling loop to the 25 source of strap supply is readily severed, comprises a pivotally mounted tongue 80 which is hinged on a bolt 81 anchored in a socket provided in rack 26 and cap 27. Tongue 80 has a strap-breaker edge 82 that lies along and just above a complementary edge 83 of the base 15. The movement of tongue 80 about its pivot 81 to 30 separate the strap-breaker edges 82-83 is limited by the rearwardly projecting heel 84 coming into contact with an upstanding ledge 85 of base 15. The strap end portion held by the gripper 35 of carriage B is trained over base 15 between the breaker edges 82-83 during the binder tensioning operation. Because the tongue 80 is freely pivoted it offers no appreciable resistance to the travel of the strap during the tensioning operation. The better practice is to make the joint 40 between the overlapping binder end portions in advance of (i. e., at the left as viewed in Fig. 1) and as closely as convenient to the breaker edges 82-83. After the joint is made the operator can 45 tilt the entire tool upwardly about the breaker edges 82-83 as a fulcrum whereupon, since the movement of tongue 80 is positively limited to a small amount by the engagement of its heel 84 upon ledge 85, a sharp bend or kink is made in 50 the strap portion thereby (which, by the way, is the portion extending from the joint to the source of strap supply), resulting in the strap being readily broken.

Fig. 12 shows how the edge type gripper 17-18 55 may be changed so that, with the same ultimate movement of the movable gripper 18, a width of strap which is not within that movement may be gripped. This may be accomplished by substituting a longer gripper plate 17' for the shorter plate 17.

Briefly reviewed, the operation of the tool is as follows, reference being particularly made to Fig. 13.

The operator encircles the package P with a 65 loop of strap taken from the source S—which conveniently may be a coil—and overlaps the loop end portions S'-S''. By squeezing grip control handle D toward handle 63 with the hand holding the tool, the operator opens the strap-edge gripper and with the other hand holding the overlapping strap portions S'-S'' loosely together he is readily able to locate the lower strap end portion in channel 16 between edge grippers 70 75 17-18. He now releases handle D, whereupon the

grippers 17-18 automatically close upon the edges of strap portion S'' to grip it edgewise.

With carriage B as close as possible to foot A and with handle C moved as far as possible counter-clockwise—to open surface gripper 32-5 34—the supply end portion S' of the strap loop is positioned between the gripper members of the movable carriage and tensioning handle C is released so that the spring-pressed biasing plunger 58 may cause shaft 40 to be rocked to move the 10 pivoted gripper 34 down upon the upper surface of strap portion S' and anchor that strap portion against foot 32. Now the tool is ready to tension the strap and, in effect, shrink the package 15 encircling loop about the package.

The operator now oscillates tensioning handle C to cause the carriage B to move step-by-step along rack bar 26 away from foot A with the result that grippers 17-18 and 32-34 are separated to pull the strap loop taut about the 20 bundle. When the desired tension is attained the strap loop end portions are joined in any appropriate manner—as previously stated, preferably immediately in front of breaker edges 25 82-83—to render the tensioned loop permanent.

After the joint is made the surface gripper 32-34 is first released, by swinging the tensioning handle C toward and against finger 38 to raise gripper 34; the edge gripper 17-18 is then released, by squeezing handle D toward handle 63; 30 next surface gripper 32-34 is again brought into action, by releasing handle C to enable the biasing spring of plunger 58 to rotate gripper 34 into contact with the strap portion S' which is still connected to the source S; and finally the entire tool is tilted—preferably by handle 63—about the breaker edges 82-83 as a fulcrum to kink and break the loop from the source. Gripper 32-34 35 may now again be released to free the tool entirely from the strap and condition it for another 40 tensioning operation.

Having thus illustrated and explained an embodiment of my invention, what I claim and desire to secure by United States Letters Patent is as follows:

1. A binder-strap tensioning tool comprising a foot adapted to rest upon the package being bound, said foot having a pair of relatively movable strap-edge gripper members at its under side and a carriage support projecting laterally therefrom, a carriage movable along said carriage support, said carriage having a pair of relatively movable gripper members, a tensioning handle pivotally mounted on the carriage, operative connections between the tensioning handle and the carriage whereby oscillations of the handle advance the carriage along said support to effect relative movement between the gripper members associated with the carriage and the gripper members associated with the foot, an edge-gripper release handle carried by the carriage support, and a release mechanism for the gripper members associated with the carriage.

2. A binder-strap tensioning tool comprising a foot adapted to rest upon the package being bound, said foot having a pair of relatively movable strap-edge gripper members at its under side and a carriage support projecting laterally therefrom, a carriage movable along said carriage support, said carriage having a pair of relatively movable gripper members, a tensioning handle pivotally mounted on the carriage, operative connections between the tensioning handle and the carriage whereby oscillations of the handle advance the carriage along said support to effect 65 70 75

- relative movement between the gripper members associated with the carriage and the gripper members associated with the foot, an edge-gripper release handle carried by the carriage support, and a release mechanism for the gripper members associated with the carriage, said release mechanism being operable by the tensioning handle.
3. A binder-strap tensioning tool comprising a foot for resting upon the package being bound, said foot having a pair of relatively movable strap-edge gripper members therebelow and a rack projecting laterally therefrom, a carriage slidably mounted on the rack and having a pair of relatively movable strap gripper members mounted thereon, a tensioning handle pivotally carried by the carriage, operative connections between the tensioning handle and the rack and one of the gripper members associated with the carriage whereby the tensioning handle may propel the carriage along the rack and may effect release of the gripper members associated therewith, a grip control handle carried by the rack, and operative connections between the last mentioned handle and one of the gripper members associated with the foot to effect the release thereof.
4. In a binder-strap tensioning tool the combination of a foot for resting on a package being bound and having a strap channel in the lower face of the foot, a stationary gripper member secured to the foot and having an active face projecting laterally into the channel to contact the edge of a strap lying in the channel, a bell crank lever pivoted to the foot on the side of the channel opposite the stationary gripper members, and a gripper member pivoted to the bell crank lever and having an active face projecting laterally into the channel to confront the stationary gripper and contact the other edge of a strap lying in the channel.
5. In a binder-strap tensioning tool the combination of a foot for resting on a package being bound and having a strap channel in the lower face of the foot, a rack projecting from the foot, a gripper movably carried on the rack, a stationary gripper member secured to the foot and having an active face projecting laterally into the channel to contact the edge of a strap lying in the channel, a bell crank lever pivoted to the foot on the side of the channel opposite the stationary gripper member, a gripper member pivoted to the bell crank lever and having an active face projecting laterally into the channel to confront the stationary gripper and contact the other edge of a strap lying in the channel, and means to cause the gripper on the rack to move therealong away from the gripper members associated with the foot.
6. In a binder-strap tensioning tool the combination of a foot for resting on a package being bound and having a strap channel in the lower face of the foot, a rack projecting from the foot, a gripper movably carried on the rack, a stationary gripper member secured to the foot and having an active face projecting laterally into the channel to contact the edge of a strap lying in the channel, a bell crank lever pivoted to the foot on the side of the channel opposite the stationary gripper members, a gripper member pivoted to the bell crank lever and having an active face projecting laterally into the channel to confront the stationary gripper and contact the other edge of a strap lying in the channel,
- means to cause the gripper on the rack to move therealong away from the gripper members, and a grip control handle mounted on the rack and connected to the bell crank lever to move the same to actuate the gripper member pivoted thereto.
7. A binder-strap tensioning tool comprising a foot to rest on a package being bound, a gripper associated with the foot to anchor one end of a binder strap thereto, a rack extending laterally from the foot, a carriage movably mounted on the rack, a gripper for the other end of a binder strap carried by the carriage, a tensioning handle pivoted to the carriage, means for translating oscillations of the tensioning handle into movement of the carriage along the rack, a strap breaker tongue pivoted to the foot and having an edge overlying a strap trained over the foot, and a positive stop for limiting the movement of the breaker tongue when the tool is rotated thereabout so that the strap is sharply bent at the end of the breaker tongue.
8. In a binder-strap tensioning tool the combination of a foot adapted to rest on a package, said foot having a strap channel in its under side, a stationary gripper at one side of the channel, a movable gripper at the opposite side of the channel, a movable member carried by the foot and carrying the movable gripper, a rack extending laterally from the foot, a carriage movable along the rack, strap grippers carried by the carriage, a grip control lever pivoted to the rack at a point thereon removed from the foot, and a rod interconnecting the grip lever and the bell crank lever whereby the grip lever can control the movable gripper at the foot.
9. A gripper for holding a package encircling binder-strap comprising two gripping members which are relatively movable in the flatwise plane of a portion of the strap interposed between them so as to clamp the strap edgewise between them, the two gripping members having strap-edge engaging faces that diverge in a direction away from the package being bound.
10. A gripper for holding a package encircling binder-strap comprising two gripping members which are relatively movable in the flatwise plane of a portion of the strap interposed between them so as to clamp the strap edgewise between them, the two gripping members having strap-edge engaging faces that diverge in a direction away from the package being bound, one face lying in a plane and the other being curved.
11. A binder-strap tensioning tool wherein a foot for resting on a package being bound carries a fixed and a movable gripper for anchoring one end portion of the strap between them and also carries an elongated carriage support having a carriage movable therealong and which carriage has a fixed and a movable gripper for gripping the other end portion of the strap, characterized by the fact that the carriage support carries a gripper control handle, and that operative connections exist between said handle and the movable gripper carried by the foot to cause operation of the handle to actuate the movable gripper carried by the foot to permit reception of a strap in gripping position.
12. A binder-strap tensioning tool wherein a foot for resting on a package being bound carries an elongated carriage support having a carriage movable therealong and which carriage has a pair of grippers for engaging one end portion of a binder strap, characterized by the fact that

the foot has a strap receiving channel on its under side and that there is combined therewith, a pair of grippers on opposite sides of the channel to engage the edges of the other end portion of a strap, a lever carrying one of the grippers so that it may be moved in parallel relation toward and away from the other gripper,

a spring biasing the lever to move the gripper carried thereby toward the other gripper, and a gripper control handle for moving the lever against the bias of the spring to separate the grippers.

5

ALFRED MARCHEV.
